US0D1077170S

(12) **United States Design Patent** (10) **Patent No.:** **US D1,077,170 S**
(45) **Date of Patent:** **** May 27, 2025**

(54) **FILTER FRAME**

(71) Applicant: **AirDoctor, LLC**, Sherman Oaks, CA (US)

(72) Inventors: **Peter G. Spiegel**, Sherman Oaks, CA (US); **Gavin Idol**, Sherman Oaks, CA (US); **Michael Pedersen**, Sherman Oaks, CA (US)

(73) Assignee: **AirDoctor, LLC**, Sherman Oaks, CA (US)

(**) Term: **15 Years**

(21) Appl. No.: **29/886,037**

(22) Filed: **Mar. 3, 2023**

(51) LOC (15) Cl. **23-04**

(52) U.S. Cl.

USPC **D23/365**

(57) **CLAIM**

The ornamental design for a filter frame as shown and described.

DESCRIPTION

FIG. 1 is a perspective view of a filter frame;
FIG. 2 is a front view thereof;
FIG. 3 is a back view thereof;
FIG. 4 is a top view thereof;
FIG. 5 is a bottom view thereof;
FIG. 6 is a right view thereof; and,
FIG. 7 is a left view thereof.

(Continued)

The broken lines shown in the figures are for the purpose of illustrating portions of the filter frame and form no part of the claimed design.
